UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

SHOE.

1,184,127.

Specification of Letters Patent. Patented May 23, 1916.

Original application filed May 21, 1913, Serial No. 768,973. Divided and this application filed September 15, 1914. Serial No. 261,820.

To all whom it may concern:

Be it known that I, ADAM H. PRENZEL, a citizen of the United States, residing at Halifax, in the county of Dauphin and State of Pennsylvania, have invented certain Improvements in Shoes, of which the following description, in connection with the accompanying drawings, is a specification, like reference characters on the drawings indicating like parts in the several figures.

This invention relates to shoes and is herein shown as embodied in a shoe of the stitch-down type, although it will be apparent that some of the features of the invention are equally applicable to shoes of other types.

In the manufacture of stitch-down shoes, and particularly in the manufacture of 20 stitch-down shoes by the staple-lasting process, it has been customary, in order that the upper may be properly supported upon the inside of the shoe and in order to take care of the edges of the lining, to provide an insole over which the lining is lasted and upon the bottom of which the lining is pasted down. This attachment of the lining to the insole has been the only attachment of the insole to the rest of the shoe except at the 25 heel end where the insole is usually attached either by tacks employed in lasting in the heel-seat, or by the nails used in the heel nailing operation. Even when the best cement has been used, it has been found that 30 this attachment of the insole is not entirely satisfactory, since with the heat and moisture of the foot it tends to separate from the lining and also tends to curl up at its edges.

40 An object of the present invention is to improve shoes of the type in which the insole and lining are secured together. To this end the insole of the shoe is so prepared before the shoe is assembled upon the last 45 that the lining may be drawn tight over the last and secured to the insole or to a connecting strip or welt strip upon the insole by permanent, preferably through-and-through, fastenings, such, for example, as 50 stitches.

A particular object of the invention is the utilization of such means and the practice of the process in such manner that insoles of comparatively inexpensive material may

be employed without detracting materially from the wearing qualities of the shoe.

The preferred method of making the shoe constituting the present invention is disclosed and fully described in United States Patent No. 1,131,415, granted March 9, 1915, 60 on an application of Adam H. Prenzel, of which the present application is a division.

In the accompanying drawings, Figure 1 is a perspective view, partly in section, showing an insole which has been prepared 65 in the preferred manner for the attachment of the lining; Fig. 2 is a cross-section showing the insole, upper and lining assembled upon the last and the lining secured to the welt strip of cloth or other material upon 70 the insole; Fig. 3 shows the manner of lasting the shoe; Fig. 4 is a broken perspective of a completed shoe, sectioned to show the relative locations of the different parts; and Fig. 5 illustrates an alternative mode of preparing the insole for the attachment of the 75 lining.

In preparing the insole 2 for the attachment of the lining 6 a welt strip 4 of cloth or other suitable material is secured by 80 stitches 5 to the bottom face of the insole so that a substantial portion of the strip projects beyond the edge of the insole. The stitching of the cloth to the insole 2 is preferably at such a distance from the edge of 85 the insole that the lining 6 may be drawn slightly over the edge, as shown in Fig. 2, during the attachment of the lining 6 to the welt strip 4. The welt strip 4 having been attached to the insole, the insole 2, upper 8 90 and lining 6 are assembled upon a last 10. The upper is then turned back somewhat from the lining 6 and the lining is drawn over the last and over the bottom edge of 95 the insole, and is secured to the welt strip 4, preferably by stitches 11. A convenient means for securing the lining 6 to the welt strip 4 is the lining lasting machine of my co-pending application Serial No. 861,877 filed of even date herewith.

100 The lining 6 and welt strip 4 having been secured together, the shoe is ready for the temporary attachment of the outsole 14 preparatory to the lasting operation. In order to provide the proper insulation of the foot 105 from the ground and at the same time to raise the insole 2 somewhat from the outsole 14 to facilitate the lasting operation, a fili-

ing piece 12 of felt, felt paper or other suitable heat insulating material is preferably placed between the outsole and the insole and the outsole is temporarily secured 5 upon the bottom of the insole in any convenient manner, as, for example, by tacks.

In laying the outsole upon the last, or upon the insole and filling piece, care is taken that the welt strip 4 and the portion of the 10 lining below the stitches 11 are turned out so as to lie between the outturned part of the upper and the outsole. The shoe is preferably lasted by staples 16 which are driven through the upper 8, lining 6 and welt strip 15 4 into the outsole 14, these staples being preferably driven at such an angle that they will not project through the bottom of the outsole and that they will extend substantially transverse to the direction of pull of the 20 stretched upper. A convenient means for lasting the shoe is the machine of United States Patent No. 1,117,087, granted March 10, 1914, on an application of Adam H. Prenzel. The shoe having been lasted in 25 the manner shown in Fig. 3, a welt 18 is laid upon the outturned portion of the upper and the welt 18, margin of the upper 8, outturned part of the lining 6, welt strip 4 of the insole and the outsole 14 are united by stitches 20. 30 In Fig. 5 is shown an alternative form of insole which requires better material for a satisfactory preparation than the insole shown in Fig. 1. In Fig. 5 the insole is slit in from its edge to form a flexible lip 22 35 which will serve the purpose of the connecting strip or welt strip.

From the foregoing description it will be noted that the completed shoe has an insole which is firmly secured to the lining through 40 the welt strip 4 or flexible lip 22 and that the insole is also secured to the outsole by reason of the fact that the line of stitches 20 which secure the welt, upper, welt strip and outsole together pass through the welt strip 45 and welt. There is thus no opportunity for

the lining or the insole to become loose or to wrinkle up and cause discomfort to the wearer.

Having described my invention, what I claim as new and desire to secure by Letters 50 Patent of the United States is:—

1. A shoe comprising an insole, a welt strip secured to the edge of said insole, a lining independently secured to said welt strip, an upper, and an outsole secured to 55 the margin of the upper.

2. A shoe, comprising an insole, a welt strip secured to the edge of said insole, a lining independently secured to said welt strip, an upper, and an outsole secured to the 60 margin of the upper and to said lining and welt strip.

3. A shoe, comprising an upper, a lining and an insole over the heel end of which the heel end of the upper and lining are lasted 65 in, a welt strip secured to said insole at points in front of the heel end and to which the lower adjacent margin of the lining is secured, and an outsole secured to the upper, lining and welt strip of the insole. 70

4. A shoe, comprising an upper, lining and an insole having stitched upon its under face a welt strip to which the lower margin of the lining is stitched, an outsole, staples securing the upper, lining and welt 75 strip to the outsole, said staples being located between the edge of the insole and the outsole, a welt having its inner edge located between the inner edge of the insole and the outsole, and stitches uniting the 80 welt, upper, lining, insole, welt strip and outsole.

In testimony whereof I have signed my name to this specification in the presence of two subscribing witnesses.

ADAM H. PRENZEL.
